[73] Assignee: **S&C Electric Company, Chicago, Ill.**

CLAIM

[**] Term: **14 Years**

The ornamental design for an interrupter switch with circuit-parameter sensing features, as shown and described.

[21] Appl. No.: **331,571**

DESCRIPTION

[22] Filed: **Mar. 30, 1989**

FIG. 1 is a perspective view of an interrupter switch with circuit-parameter sensing features showing our new design;

[52] U.S. Cl. **D13/160**

FIG. 2 is a front elevational view thereof;

[58] Field of Search ..... **D13/158, 160, 169, 129-132; 200/48 R, 48 P, 48 A, 48 B, 146 R**

FIG. 3 is a rear elevational view thereof;

[56] References Cited

FIG. 4 is a right side elevational view thereof;

U.S. PATENT DOCUMENTS

FIG. 5 is a left side elevational view thereof;

3,163,736 12/1964 Mikos et al. ..... 200/146 R X

FIG. 6 is a top plan view thereof;

3,627,939 6/1970 Myers ..... 200/48.5 B

FIG. 7 is a bottom plan view thereof.

4,049,936 9/1977 Frink et al. ..... 200/48 R X

FIG. 1

FIG. 2

FIG. 4

FIG. 5

FIG. 6

FIG. 7
